(57) CLAIM

The ornamental design for a storage closure, as shown and described.

DESCRIPTION

In a preferred embodiment, the nature of this product is a closure for covering the opening of an enclosure and providing storage space, such as for enclosing the opening of a shower or tub area and storing related items.

FIG. 1 is a right, top, front perspective view of our new design;

FIG. 2 is a right, top, rear perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof;

FIG. 8 is a bottom plan view thereof; and,

FIG. 9 is a front elevational view of another embodiment of our new design having views that are mirror images of the views shown in FIGS. 1-2 and 4-8.

The broken line representations of wall, door, frame and/or shelving environment in the figures are for the purpose of illustration only, and form no part of the claimed design.
